US00D419180S

United States Patent [19]

Yasoshima

[11] **Patent Number: Des. 419,180**
 [45] **Date of Patent: ** Jan. 18, 2000**

[54] **STAMP PAD CONTAINER**

- [75] Inventor: **Rira Yasoshima**, Tokyo, Japan
 [73] Assignee: **Tsukineko, Inc.**, Redmond, Wash.
 [**] Term: **14 Years**
 [21] Appl. No.: **29/083,399**
 [22] Filed: **Dec. 31, 1997**
